UNITED STATES PATENT OFFICE.

HARRY B. LATINA, OF EAST ST. LOUIS, ILLINOIS, ASSIGNOR TO RAWLINGS MANUFACTURING COMPANY, OF ST. LOUIS, MISSOURI, A CORPORATION OF MISSOURI.

SHOULDER PAD.

Application filed May 4, 1925. Serial No. 27,771.

This invention relates to shoulder pads such as are used by foot ball players.

One object of my invention is to provide a shoulder pad in which the shoulder caps 5 are connected with the two main sections of the pad in such a manner that they are free to move forwardly and rearwardly relatively to said main sections in circular paths, and thus not interfere with or restrict the movements of the user's shoulder in the operation 10 of making a forward pass in the game of foot ball.

Another object of my invention is to provide a shoulder pad in which the main sections 15 of the pad that protect the bony process on the user's shoulders are equipped with a novel means for effectively absorbing blows and shocks imposed on said main sections when the pad is in use. Other objects and 20 desirable features of my invention will be hereinafter pointed out.

Figure 1 of the drawings is a front elevational view, illustrating a shoulder pad constructed in accordance with my invention, 25 arranged in operative position on the shoulders of the user.

Figure 2 is a perspective view of one of the two main sections of the pad, illustrating the shock absorbing means on the underside 30 of said section, and showing how the shoulder cap of said section is connected with same; and

Figure 3 is a longitudinal sectional view of one of the main sections of the pad and 35 its co-operating shoulder cap.

Referring to the drawings which illustrate the preferred form of my invention, A designates the two main sections of the pad which are shaped so that they can be arranged on 40 the shoulders of the user, as shown in Figure 1, and which are constructed so that they will protect the bony process on the shoulders. Usually, said sections A will be constructed from pieces of molded fibre 45 covered with felt, but the particular construction of the sections A is immaterial, so far as my invention is concerned, so long as they consist of substantially rigid or stiff members that are capable of successfully 50 withstanding severe blows or shocks. I have herein illustrated the sections A as being retained in operative position on the user's shoulders by connecting straps 1 that are detachably connected to said main sections 55 A by ball and socket fasteners 2, but any

other means can be used for joining the sections A together without departing from the spirit of my invention.

The shoulder caps B of the pad, which are also constructed in the form of substantially rigid or stiff members shaped so as to conform approximately to the tips of the user's shoulders, are connected to the main sections A of the pad in such a way that they are free to oscillate forwardly and rearwardly relatively to the sections A when the user throws a ball, for example, during the operation of making a forward pass. I am aware of the fact that it is old in shoulder pads to hinge the shoulder caps to the main sections of the pad or connect said parts together by lacings that permit the shoulder caps to be adjusted inwardly and outwardly, and also forwardly and rearwardly relatively to the main sections of the pad, but in such prior shoulder pads the shoulder caps were not free to oscillate or move in circular paths, and accordingly, said shoulder caps interfered with and restricted the free movement of the user's shoulder in the operation of using the arm to throw a ball. In my improved shoulder pad the shoulder caps B are capable of practically a universal movement relatively to the main sections A of the pad, namely, they are free to swing upwardly and downwardly in a vertical direction, they are free to swing 75 forwardly and rearwardly and they are also free to oscillate forwardly and rearwardly in circular paths similar to the elements of a ball and socket joint, the concaved end portions of the main sections A of the pad constituting the sockets and the convexed shoulder caps B constituting the balls of the joints.

Various means can be used for effecting such a connection between the shoulder caps B and the sections A of the pad, but I prefer to connect each of the shoulder caps B to its co-operating section A by a member 100 C that extends inwardly from the inner end of the shoulder cap and which is pivotally connected at 3 to the underside of the section A at a point adjacent the longitudinal center of said section and in comparatively 105 close proximity to the inner curved edge 4 of the section. The member C is formed of leather or some other suitable material that is pliable or flexible and the shoulder cap B is secured to the outer end of the member C 110

2
by a row of stitches 5, or any other suitable means that acts similar to a hinge between the member C and cap B, and thus permits said cap to rock vertically relatively to said member. The shoulder caps B are held in engagement with the tips of the user's shoulders by straps 6 that extend under the user's arm pits, as shown in Figure 1, and consequently, when the user's arm is moved to throw a ball, particularly in the operation of making a forward pass, the member C which carries the cap B that covers the tip of the user's shoulder will turn on its pivot 3 and also flex sufficiently to permit the cap B to rotate forwardly, and thus not interfere with the movement of the user's arm or shoulder. In other words, in my improved shoulder pad the convexed shoulder caps B that are held down snugly on the tips of the user's shoulders are free to revolve slightly in the concaved portions of the main sections A of the pad which lap over said caps, and accordingly, do not restrict the movement of the user's shoulder in the operation of throwing a ball. The pivotal connections 3 between the extensions C on the shoulder caps B and the main sections A of the pad may be formed by ball and socket fasteners, and if desired, said extensions can be lined on their undersides with pieces of felt 7.

In the conventional shoulder pad used by foot ball players the main sections of the pad are padded on their under sides so as to prevent said sections, which are stiff and rigid, from injuring the user's shoulders in the event said sections are subjected to severe blows or shocks. In my improved pad no such padding is used on the underside of the main sections A of the pad, but instead, said main sections are equipped with shock absorbing devices that normally hold the sections A spaced away from the user's shoulders, but which effectively absorb severe blows or shocks on said sections A. In the form of my invention herein illustrated the shock absorbing devices just referred to are formed by relatively wide strips of inelastic webbing 8 arranged transversely on the undersides of the main sections A of the pad in such a manner that when the pad is in operative position on the user's shoulders, the devices 8 will contact

with the user's shoulders and prevent the rigid top portions of the sections A from bearing upon the shoulders, the devices 8 extending transversely of the sections A at points below the inwardly-projecting extensions C on the shoulder caps that are pivotally connected at their inner ends to the sections A, as shown more clearly in Figure 2. In the event either section A of the pad is subjected to a severe blow or shock, the device 8 on the underside of said section that bears upon the user's shoulder will absorb the blow and prevent the top portion of the section A from moving downwardly into engagement with the shoulder.

Having thus described my invention, what I claim as new and desire to secure by Letters Patent is:

1. A shoulder pad for foot ball players, comprising sections shaped to fit over the user's shoulders, shoulder caps, and flexible, inwardly projecting extensions on said caps pivotally connected to the underside of said sections at points adjacent the curved edges of said sections which surround the user's neck.

2. A shoulder pad for foot ball players, comprising main sections shaped to fit over the user's shoulders, shoulder caps, flexible members projecting inwardly from the inner ends of said shoulder caps and connected to same by hinged joints, and means for detachably and pivotally connecting said flexible members to the underside of said sections.

3. A shoulder pad for football players, comprising substantially rigid or inflexible sections that fit over the user's shoulders, shoulder caps provided with inwardly-projecting, flexible extensions that are pivotally connected to the underside of said sections at points adjacent the inner ends of said sections, means for holding said caps in engagement with the tips of the user's shoulders, and substantially inelastic elements arranged transversely on the underside of said sections at points below the inwardly-projecting extensions on the shoulder caps and connected to said sections so as to form devices that will absorb shocks and blows to which said sections are subjected.

HARRY B. LATINA.
